UNITED STATES PATENT OFFICE.

HERBERT CORRALL, OF HELENSBURGH, SCOTLAND, ASSIGNOR TO THE SINGER MANUFACTURING COMPANY, A CORPORATION OF NEW JERSEY.

SEWING-MACHINE.

1,397,622.

Specification of Letters Patent.

Patented Nov. 22, 1921.

Application filed February 19, 1918. Serial No. 218,016.

To all whom it may concern:

Be it known that I, HERBERT CORRALL, a subject of the King of the United Kingdom of Great Britain and Ireland, and residing 5 at Helensburgh, Dumbartonshire, Scotland, have invented a certain new and useful Improvement in Sewing-Machines, of which the following is a specification.

This invention relates to an improvement 10 in overseaming sewing machines of the type particularly adapted for attaching, by means of overedge stitches, the insoles to the uppers of felt or cloth slippers.

In the manufacture of this class of foot- 15 wear it has heretofore been customary to secure the insole to the upper by hand sewing. An object of the present invention is the construction of a sewing machine which will replace the operation of hand sewing and 20 thereby result in a more uniform and neater product at a decreased cost.

The usual form of fur or glove sewing machine, fitted with opposed feed and presser-wheels, normally in contact, has been found 25 to be unsuitable for attaching the insoles to the uppers in that the presser-wheel interfered with the proper placing of the overseaming stitches at the toe and heel portion of the slipper where a free manipulation of 30 the material was found to be essential in the stitching operation.

According to the invention there is adapted 35 to the sewing machine, provided with a step-by-step rotatable feed wheel engaging the material to be stitched, a presser mechanism, the presser member of which is normally held out of engagement with the material but is brought into, and maintained in, engagement with the material during the 40 period requisite for the proper formation of the stitch.

Figure 1 of the accompanying drawings is 45 an elevation and Fig. 2 a plan of a practical construction of sewing machine embodying the invention. Fig. 3 is a detail sectional view.

The improvement is embodied in a machine provided with a base 15 from which rises the hollow upright standard 16 which 50 is provided with suitable bearing lugs in which is journaled the main-shaft 4 trans-

versely of the standard. Disposed in front of the standard is the vertical shaft 17 carrying the feed-wheel 11.

In the construction shown the presser bar 55 1, is endwise movable in horizontal bearings transversely of the main-shaft. It is surrounded by a block 2 slidable thereon and receives reciprocatory movements in the axial direction of the presser-bar 1 from a 60 moving part of the machine, for example from an eccentric 3 on the main shaft 4 embraced by an eccentric strap 5 connected to an arm 6 rocking on a fulcrum 7 disposed near the base of the machine frame, the 65 upper end of the arm 6 being pivotally connected to the block 2 by means of a link 6'.

Clamped near the forward end of the presser-bar 1 is the U-shaped arm 12 carrying near its free end the presser 13 between 70 which and the feed-wheel 11 the material is held during the period requisite for the proper formation of the stitch.

Fixed to the presser bar 1, between the block 2 and the presser 13, is a stop or collar 75 8 engageable by the block 2 whereby movement of the block 2 in the direction to bring the presser out of engagement with the work is positively transmitted to the presser-bar 1.

On the opposite side of the block 2 is a 80 spring, for example a helical spring 9, which, if the presser bar be of tubular formation, may be accommodated within the presser-bar 1, one end of the spring engaging a stop 2' secured in fixed relation with the block 85 2 by the bolt 2'' (see Fig. 3) and the other end engaging a preferably adjustable abutment, for example a screw or bush 10 threaded into or on to the end of the presser-bar, by adjustment of which screw or bush 10 90 the spring 9 may be subjected to any required degree of initial stress.

As will be evident, when the block 2 is moved in the direction to bring the presser into engagement with the work fed by the 95 wheel 11, the block 2, the bar 1 and the spring 9 will be moved as a whole, until resistance is offered to the presser by the work. In the further movement of the block 2 the spring will be further compressed, and the 100 presser will be resiliently pressed against the work—the pressure on the work being

proportionate to the thickness of the goods being handled.

Inasmuch as the spring 9 is continuously in engagement with the block 2, and the 5 spring 9 is only under slight stress at the time the presser comes into engagement with the work, the movement of the presser into engagement with the work is unaccompanied by shocks so that wear is minimized and 10 silence of operation is insured.

In the reverse movement of the block 2 and consequent movement of the presser away from the work, the spring 9 is automatically unstressed.

15 The machine is equipped with a stitch-forming mechanism common to the usual fur or glove type of machine and may be such as is disclosed, for instance, in the patent to James Heggie, No. 1,094,715, of April 20 28, 1914, of which only the reciprocating 20 needle 14 of the present improvement is shown.

During the operation of the machine the presser 13 clamps the material being stitched 25 against the feed-wheel 11, which thereby receives the thrust of the needle 14 while it penetrates the material, the presser and feed-wheel rigidly holding the material during the period requisite for the proper formation of the stitch. When the stitch has 30 been completed the presser recedes from the feed-wheel to permit a free manipulation of the material, which, in the meantime, is held against the feed-wheel by hand.

35 What I claim is:—

1. In a sewing machine, in combination, a feed-wheel against which the material is held during the feed movements thereof, a presser opposed to said feed-wheel, a main-shaft and connections for shifting the presser toward and away from the feed-wheel, said 40 connections including a to-and-fro moving actuator, and a spring interposed between said actuator and presser and adapted to be compressed by the actuator in forcing the presser toward the feed-wheel.

2. In a sewing machine, in combination, a base having a hollow upright standard, a feed-wheel against which the material is held manually during the feed movements 50 thereof, a presser opposed to said feed-wheel, a main-shaft and connections for shifting the presser toward and away from the feed-wheel and holding it in such position during the feed, said connections including a to-and-fro moving actuator, a longitudinally 55 slideable presser-bar carrying said presser and mounted in said standard, and a spring interposed between said actuator and said presser-bar for compression by the actuator in forcing the presser toward the feed-wheel.

3. In a sewing machine, in combination, a base having a hollow upright standard, a 60 feed-shaft disposed vertically in front of

said standard, a feed-wheel carried by said shaft against which feed-wheel the material is held manually during the feed movements thereof, a presser opposed to said feed-wheel, a main-shaft journaled transversely of said feed-shaft and supported by said standard, and connections for shifting the presser toward and away from the feed-wheel and holding it in retracted position during the feed, said connections including 70 a to-and-fro moving actuator, a longitudinally slideable presser-bar supported in said standard transversely of said main- and feed-shafts and carrying said presser, and a spring interposed between said actuator and 75 said presser-bar for compression by the actuator in forcing the presser toward the feed-wheel.

4. In a sewing machine, in combination, a tubular presser-bar, a presser carried by 80 said bar, a stop for said bar, a reciprocatory member movable longitudinally of said bar and into engagement with said stop to positively force the presser away from the material, and a spring within said tubular bar 85 and continuously in engagement with said reciprocatory member to force the presser yieldingly against the material.

5. In a sewing machine, in combination, an endwise-movable presser-bar, a presser 90 carried by said bar, a stop for said bar, a reciprocatory member movable longitudinally of said bar and into engagement with said stop to positively force the presser away from the material, a spring in continuous engagement with said reciprocatory member to force the presser yieldingly against the material, and means for varying the initial stress of said spring.

6. In a sewing machine, in combination, 105 an endwise-movable presser-bar, a presser carried by said bar, a reciprocatory member movable positively longitudinally of said bar and adapted to impart thereto endwise movements to positively force the presser 110 away from the material, a spring interposed between said reciprocatory member and said bar and means including an eccentric for imparting movements to said reciprocatory member to force the presser yieldingly 115 against the material.

7. In a sewing machine, in combination, a base having a hollow upright standard, a main-shaft journaled transversely of and supported by said standard, a presser-bar extending transversely of said main-shaft and 120 slidably supported by said standard, and means connected with said main-shaft for reciprocating said presser-bar.

8. In a sewing machine, in combination, 125 a base having a hollow upright standard, a main-shaft journaled transversely of and supported by said standard, a presser-bar extending transversely of said main-shaft and slidably supported by said standard, a 130

shaft disposed vertically in front of said standard, a feed-wheel carried thereby, means connected with said main-shaft for reciprocating said presser-bar, and a presser 5 carried by said presser-bar and adapted to intermittently clamp the work against the feed-wheel.

In testimony whereof I have signed my name to this specification in the presence of two subscribing witnesses.

HERBERT CORRALL.
